No. 790,663.

PATENTED MAY 23, 1905.

G. D. SMITH.

RAILWAY FROG.

APPLICATION FILED FEB. 7, 1905.

UNITED STATES PATENT OFFICE.

GEORGE D. SMITH, OF PATERSON, NEW JERSEY.

RAILWAY-FROG.

SPECIFICATION forming part of Letters Patent No. 790,663, dated May 23, 1905.

Application filed February 7, 1905. Serial No. 244,525.

To all whom it may concern:

Be it known that I, GEORGE D. SMITH, a citizen of the United States, residing in Paterson, Passaic county, New Jersey, have invented 5 certain new and useful Improvements in Railway-Frogs; and I do hereby declare the following to be a full, clear, and exact description of the invention, such as will enable others skilled in the art to which it appertains to 10 make and use the same, reference being had to the accompanying drawings, and to letters of reference marked thereon, which form a part of this specification.

My invention relates to railway-frogs, and 15 it has reference particularly to that type of frog wherein the wings are pieces (rails) separate from each other and bent to have the required shape so as to match with the adjacent rails at one end and be properly spaced from 20 the point of the frog at the other end. Frogs of this type wear most on the point near its extremity and also on the wings just beyond the tip or extremity of the point, because here the wheels act with an impact or sudden jar 25 or blow on the frog. Heretofore nothing has been done to compensate in the same mechanism for this wear. When the parts are worn out, as just explained, the frog was considered useless and had to be entirely removed 30 and replaced by a new one. This means a considerable expense, especially where the frog is one which is in frequent use.

By my invention the life of the frog is doubled and the expense of equipment in the mat- 35 ter of frogs cut down in proportion.

My invention will be found fully illustrated in the accompanying drawings, wherein—

Figure 1 shows it as applied to a plain frog. Fig. 2 shows it as applied to what is commonly 40 known as a "spring-rail" frog. Fig. 3 is a transverse sectional view on the line $\alpha\alpha$ in Fig. 1; and Fig. 4 is a view like Fig. 3, showing a means for compensating for the wear on the point of the frog.

In the ordinary frog of the kind in view 45 the rails forming the wings are made sufficiently long and bent at such an angle at one end that they will match with the adjacent rails; but at the other end they are bent off 50 with regard only to securing enough clearance between themselves and the point of the frog so that the wheel-flanges will not ride up onto

them, usually in a curve. My invention contemplates making both end portions of the wings alike—that is to say, bending them both 55 at an angle and to the same degree and preferably giving both the same length from the angles to the extremity. Then when the wings wear at the points above referred to—namely, just beyond the tip of the point and where 60 the wings begin to project most nearly to each other—they may be removed, reversed end for end, and made to interchange positions, so that the wear will now come on the as yet un- 65 used parts thereof.

In the drawings, a represents the ties, b the wings, and c the point, bolted together and held in the proper spaced relations by filler-blocks c' . The rails to be matched by the wings are shown in dotted lines at d .

e denotes the ends of the wings, which are shaped (as at present) to match with the rails d , and f the ends, shaped in accordance with my invention to conform to the ends e , so that they will match the rails d upon removing 75 the wings, reversing them end for end, and interchanging their positions.

Since the point of the frog also wears, I contemplate placing this in the same renewed condition as the wings after reversal by driving a wedge g under the point, (see Fig. 4,) thereby raising its top surface to the level of the top surfaces of the wings.

Having thus fully described my invention, what I claim, and desire to secure by Letters 85 Patent of the United States, is—

1. A railway-frog having its wings separate from each other, the end portions of each wing being bent off at angles at the same degree and being of the same length from the 90 angles to their extremities, substantially as described.

2. A railway-frog having separable wings formed end for end alike, in combination with means for elevating the point of the frog, substantially as described.

In testimony that I claim the foregoing I have hereunto set my hand this 3d day of February, 1905.

GEORGE D. SMITH.
